SKYLIGHT CONSTRUCTION

Aloyzius R. Blaski, Chicago, Ill., assignor, by
mesne assignments, to Frank Hussey, Chicago,
Ill.

Application February 13, 1931. Serial No. 515,513

20 Claims. (Cl. 108—16)

My invention relates to skylight construction and has for its object the provision of a new and improved form and arrangement of parts whereby the construction of either a stationary skylight or a movable ventilating skylight may be facilitated, whereby there shall be increased flexibility in the matter of making the factory-prepared parts fit different conditions on the job, and whereby there shall be the maximum of strength in proportion to the weight of material employed.

To these ends, it is one of the objects of my invention to provide improved means for connecting together the bars making up the frames which support the glass of the skylight, and particularly to provide an improved arrangement by which the side and intermediate bars which extend in inclined position between the top and bottom rails of the frame are capable of being secured very firmly in position in any desired location longitudinally of the rails with a minimum of work on the job for supporting pieces of glass of different widths.

It is another object of my invention to provide improved frame bars in the form of extruded structural shapes of aluminum alloy so shaped as to provide the desired bearings for the parts and as to have the requisite strength with respect to the stresses applied thereto in ordinary use.

It is another object of my invention to provide an improved form of hinging means for the sections employed in a ventilating skylight structure such that the sections may be easily operated and whereby they shall be held firmly against displacement by the wind when in either a fully closed position or in a fully opened position.

It is another object of my invention to provide an improved arrangement of bearing surfaces for the glass and putty whereby a more secure joint may be procured between the glass and the frame.

It is another object of my invention to provide improvements in devices of this type in sundry details hereinafter pointed out. The preferred means by which I have accomplished my several objects are illustrated in the drawings and are hereinafter specifically described. That which I believe to be new and desire to cover by Letters Patent is set forth in the claims.

In the drawings,—

Fig. 1 is a vertical section through a ventilating skylight embodying my improvements, the closure section at one side being shown in open position and being broken away for clearness of illustration;

Fig. 2 is a cross section through one of the

intermediate cross bars which extend between the top and bottom rails of the structure of Fig. 1, and showing the pieces of glass in position thereon;

Fig. 3 is a vertical cross section through my improved bottom rail as shown in Fig. 1;

Fig. 4 is a vertical cross section through the top rail of said Fig. 1;

Fig. 5 is a view similar to Fig. 2, but showing the arrangement at the end of the skylight rather than at an intermediate point;

Fig. 6 is a vertical section taken at line 6—6 of Fig. 1;

Fig. 7 is a view similar to Fig. 1 but showing a modified form of structure as applied to a stationary skylight;

Fig. 8 is a perspective view, partly in section, showing a short length of the form of ridge pole structure as used in Fig. 7;

Fig. 9 is a perspective view, partly in section, showing the form of the upper end portion of the cross bar by which it is enabled to have notched engagement with the ridge pole structure as shown in Fig. 7.

Fig. 10 is a sectional view taken at the end of the skylight section as shown in Fig. 7, being taken as looking obliquely upwardly toward the ridge pole;

Fig. 11 is a vertical section through the curb and associated parts at the end of the skylight immediately below the end cross bar as shown in Fig. 10;

Fig. 12 is a cross sectional view through a modified form of intermediate cross bar;

Fig. 13 is a cross sectional view through another modified form of cross bar, and showing the pieces of glass mounted in position thereon; and

Fig. 14 is a view showing a modified form of connection between the cross bars and the ridge pole structure, and showing the enclosure glass in position.

Referring now to Figs. 1 to 4, in which corresponding parts are indicated by the same reference characters, 20 indicates a side plate comprising a portion of the curb of my improved skylight construction. 21 indicates an angle bar extending from the plate 20 at one side of a skylight opening to a similar plate at the opposite side not shown. An upright bar 22 rising from the middle portion of the horizontal bar 21 is connected at its upper end with rafters 23. The gable end, in the construction shown, is closed by a piece of sheet metal 24 (see Figs. 5 and 6). At the upper end of the upright bar 22 at the end of the skylight, a heavy cast plate 25 is se- 110

cured in position upon the upper edge of the sheet 24, one of such plates being provided at each end of the structure for supporting sheet metal ridge pole members 26 and 27, as is best shown in Fig. 1. The vertically spaced members 26 and 27 may, of course, be connected at intervals by bracing and spacing means if desired.

The bottom rail of my improved closure section is best shown in Fig. 3, in the form of an 10 extruded structural shape of aluminum alloy, comprising a web portion 28 having an upwardly extending flange 29 near the upper edge of the web, the outer edge portion 30 of said flange being turned downwardly parallel with the web

15 28. At its lower edge portion, the web 28 is provided with a return bend portion 31 substantially opposite the downwardly turned edge portion 30, the upper edge of the return bend portion 31 being provided with an oblique flange portion 32.

20 20 A horizontally disposed flange 33 is provided at the lowermost return bend portion, and a downwardly extending flange 34 is provided at this same point.

The top rail of my improved structure is likewise in the form of an extruded structural shape 25 of aluminum alloy comprising a web 35 having a return bend portion 36 at its lower edge, at the upper edge of which is provided a flange 37 extending obliquely downwardly. The web 35 is offset slightly at an intermediate point, and the upper edge portion 38 thereof is in angular position with respect to the position of the main portion of the web. Flanges 39 and 40 are provided in spaced relation to each other on the inner 30 face of the top rail, the flange 40 being provided at its outer edge with a downwardly turned flange portion 41 located opposite the return bend portion 36. As is clearly shown in Figs. 3 and 4, the upper faces of the flanges 29 and 40 are provided with longitudinally extending ribs being 35 made possible by reason of the production of the rails by an extrusion operation.

The cross bar as shown in Fig. 2, and the cap device also shown in said figure are also in the 40 form of extruded structural shapes of aluminum alloy. The cross bar comprises a web 42 provided with laterally disposed flanges 43 at opposite faces thereof near its upper edge, and provided with trough-shaped laterally disposed 45 flanges 44 at its lower edge of said width as to extend outwardly beyond the edges of the flanges 43. The upper edge portion of the web 42 is made considerably heavier for the purpose of providing bearings for securing screws as hereinafter set forth. The cap as shown in Fig. 2 is in the form of a channel with outwardly extending flanges at opposite sides, the cap as a whole being indicated by the numeral 45. The bottom faces of the flanges of the cap 45 and the top faces of the flanges 43 of the cross bar are provided with longitudinally extending ribs, and the bottom faces of the flanges 44 are longitudinally corrugated.

In the arrangement shown in Fig. 1, the top 50 and bottom rails are arranged in spaced relation to each other with a length of cross bar extending therebetween, the cross bar being provided at each end with a bracket 46 secured in position by means of a bolt 47. Each of the brackets 46 comprises a head portion 48 of greater scope than the lug portions by which the brackets are secured in position, the arrangement being such that the brackets are adapted to have a dove-tailed connection with the top and bottom rails, the downwardly directed flanges

55 30 and 41 of the bottom and top rails respectively being adapted to extend into notches formed in the brackets, as is clearly shown in Fig. 1.

An end cross bar is provided at each end of the closure section, as is clearly shown in Fig. 5, such end cross bar comprising a web portion 49 having laterally extending flanges 50 and 51 formed on one face thereof near the upper edge of the web portion, and having a trough-shaped flange 52 thereon a short distance above the lower edge of the bar. The upper face of the flange 51 is provided with longitudinally extending ribs and the bottom face of the flange 52 is corrugated, the cross bar being in the form of an 60 extruded structural shape of aluminum alloy whereby such special forms can readily be produced.

In practice, an end rail of the type shown in Fig. 5 and as above described is connected between the top and bottom rails by means of brackets 46, such brackets being connected with the web 49 of the cross rail by means of bolts 47, and being connected with the top and bottom rails by means of machine screws such as the 65 screws 53 as shown in Fig. 1 which extend through openings in the top and bottom rails and are tapped into screw threaded openings in the brackets. The arrangement is such that the flange 29 of the bottom rail stands directly opposite to the flange 51 of the end rail at its lower end, and such flange 51 at its upper end stands directly opposite to the flange 40 of the upper rail. With the parts in such arrangement, a piece of glass 54 (see Fig. 5) is placed in position 70 upon the flanges 51, 29 and 40, imbedded in putty thereon so as to fill the space adjacent to the end bar between the top and bottom rails. An intermediate cross bar is next secured slidably in position in the top and bottom rails by means of 75 brackets 46 so as to be moved longitudinally of the top and bottom rails into the desired position for receiving the edge of the glass above the flange 43 at that side of the bar, a suitable supply of putty being provided upon such flange for 80 providing the desired tight joint. A second piece of glass 55 is then placed in position in a proper bed of putty upon the flanges 43, 29 and 40, and a second intermediate cross bar is secured in 85 position at the opposite edge of such piece of glass 55. When the closure section has reached the desired length, after the insertion of the required number of pieces of glass and intermediate cross bars, the opposite end of the closure section is arranged in substantially the same way 90 as is above described in connection with the construction as shown in Fig. 5.

By the provision of the slidably mounted intermediate cross bars, I am enabled to adapt my construction to any available width of glass. In 95 practice, I prefer to employ machine screws 53 as shown in Fig. 1, one of such screws being employed for holding each of the brackets 46 in position, but it will be understood that this is not in any way essential to an operative device. After the pieces of glass and the intermediate cross bars have been secured in position, a cap 100 45 is secured in position by means of screws 56 at each point between two adjacent pieces of 105 glass, as is best shown in Fig. 2.

The arrangement is preferably such that the bottom bar of the closure section rests directly upon the curb plate 20 or upon the flashing at this point if a flashing is used. In the construc- 110

tion shown in Fig. 1, a flashing 57 is employed at the face of the curb.

In the arrangement shown in Fig. 1, the closure section is hingedly mounted in position by means of an upwardly turned flange 58 at the edge of the ridge member 27, the lowermost portion of the top rail being bent at a fairly sharp angle for providing in effect a knife support for the rail in the angle between the flange 58 and the main portion of the plate 27. In the arrangement shown, the angular upper edge portion 38 of the top rail is brought into close relationship with the top ridge pole plate 26, the lower edge of such ridge pole plate 26 being turned downwardly and inwardly for providing a flange 59 adapted normally to stand in close proximity to the flange 39 of the top rail.

By the provision of the trough shaped flanges 44 at opposite sides of the intermediate rails, I am enabled to take care of any water which might possibly find its way through the joint between the pieces of glass, such water being adapted to flow down the troughs provided by the flanges 44 and to empty into the gutter provided by the return bend portion 31 of the bottom bar, such moisture being adapted to escape onto the roof through an opening 31a in suitable position through the web 28. Any water of condensation which may gather upon the lower faces of the flanges 44 is caused to flow down the grooves of the corrugations so as to empty into the gutter provided by the return bend portion 31, the flange 32 being adapted to insure this result, being disposed obliquely downwardly toward the bottom rail while being at the same time in divergent position upwardly with respect to the bottom faces of the cross bars.

Referring now to Figs. 7 to 12 inclusive, in which corresponding parts are indicated by the same reference characters, 60 indicates the side bars of a curb connected at their ends by transverse curb bars 61. In the arrangement shown in Fig. 7, it is not necessary to use an arrangement of rafters as is shown in connection with Fig. 1, since the stationary closure sections are themselves adapted to support the load. In the arrangement shown in Fig. 7, a bottom rail 62 is employed of substantially the same arrangement as that above described, except that a flange 63 is employed extending obliquely downwardly and inwardly in lieu of the horizontally disposed flange 33 of the bottom rail first described, and except that a downwardly extending flange 64 is employed differing slightly from the vertical flange 34. The flange 64 is secured permanently in position by means of bolts 65 passing through the flange and through an angle bar 66 fixedly mounted upon the curb bar 60. The arrangement as shown in Fig. 7 does not require the use of a top rail such as is shown in connection with the construction of Fig. 1. In lieu of such top rail, a ridge pole construction 67 is employed for holding the cross bars in position. In the arrangement shown, the ridge pole is in the form of an extruded structural shape of aluminum alloy comprising a vertically disposed web 68 and obliquely disposed spaced flanges 69 and 70 at each side of the web. The upper faces of the flanges 70 are provided with longitudinally extending ribs corresponding to the ribbed arrangement of the bars as shown in Fig. 1.

The cross bars employed in the arrangement as shown in Fig. 7 for the stationary skylight structure are in the form of extruded structural

forms of aluminum alloy originally formed very much like the intermediate cross bars as shown in Fig. 2, except that they are provided with laterally extending flanges 71 at the upper edges of the vertically disposed web 72, such flanges 71 being in spaced relation to the flanges 73 which correspond with the flanges 43 of the first described cross bar. For the joint between the upper ends of the cross bars and the ridge pole structure, the flanges 70 of the ridge pole construction are notched at their side edges at 74 for receiving a key portion 75 of the web 72, as is clearly shown in Fig. 9, the web 72 also being notched at 76 for receiving a portion of the web 70. For permitting this arrangement, the end portions of the flanges 73 are cut loose from the web 72 and are bent downwardly so as to stand in contact with the lower faces of the flanges 70, as is clearly shown in Fig. 7. By this arrangement, the cross bars are connected with the ridge pole construction so as to be held against movement vertically with respect to the ridge pole structure and so as to be held against movement longitudinally of such ridge pole construction. The upper faces of the flanges 73 are provided with longitudinally extending ribs, and the bottom faces of the trough forming flanges 77 are corrugated.

As is clearly shown in Fig. 9, the web 72 of the cross bar is extended slightly beyond the upper ends of the trough flanges 77 so as to provide a fastening lug 78, such lug portion being offset laterally to a slight extent to provide for the connection of two oppositely disposed cross bars to each other by a bolt 79 as is clearly shown in Fig. 7. The lower ends of the cross bars are provided with brackets 46 by which sliding engagement is effected with the bottom rail in the manner above described in connection with the construction of Fig. 1.

The end cross bar as shown in Fig. 10 is of the same arrangement as that shown in Fig. 2, comprising a vertically disposed web 80 having bearing flanges 81 near its upper edge and through flanges 82 extending laterally at its lower edge, corresponding with the flanges 43 and 44 of the earlier described structure. As is clearly shown in Fig. 10, the sheet metal closure member 83 which closes the gable end is turned outwardly and downwardly at its upper end providing a flange 84 which has snug engagement with a sheath flashing 85 which is secured in position upon the cross bar by means of a plurality of screws 86, the inner edge of the flashing bearing upon the top face of a piece of glass 87 imbedded in putty upon the bearing flange 81. As will be readily understood, the piece of glass 87, and the other pieces of glass at opposite sides of the intermediate cross rails have their lower ends imbedded in putty upon the flange 29 of the bottom rail, and their upper ends imbedded in putty between the flanges 69 and 70 of the ridge pole structure. An intermediate piece of glass 88 is shown in Fig. 7.

As is clearly shown in Fig. 11, in the construction illustrated the lower edge of the closure member 83 stands opposite to an angle bar 89 secured upon the sill member 61, in the construction shown a flashing 90 being interposed between the closure member and the angle bar.

As is clearly shown at the lower portion of Fig. 7, a trough 91 of any suitable type is supported by brackets 92 above the sill member 61 underneath the obliquely disposed flange 63 in position to receive the water from the gutter pro-

150

vided by the bottom rail, openings 93 being provided for the escape of the water into such trough.

In Fig. 12, I have shown a vertical cross section of the intermediate cross rail employed in the 5 construction of Fig. 7.

Inasmuch as the arrangement and operation of the construction as shown in Figs. 7 to 12 is very similar to that already described in connection with Figs. 1 to 6, it is believed to be unnecessary 10 to describe the same further herein.

In Fig. 13, I have shown a modified form of cross rail for use in connection with the structure of either Fig. 1 or Fig. 7. This modified form of rail comprises a vertically disposed web portion 15 94 which is thickened at its upper edge portion to receive a machine screw 95, bearing flanges 96 being provided at the top edge of the web portion rather than at a point slightly below such top edge as is shown in Figs. 2 and 12. Trough 20 flanges 97 are provided corresponding to the flanges 44 and 77 of the formerly described structures. A cap 45 is held in position by the screws 95 above the edges of pieces of glass 98 and 99 which are imbedded in putty as above described.

The construction shown in Fig. 14 is slightly 25 different from that shown in Fig. 7. The original form of the cross bar as shown in Fig. 14 is the same as that shown in Figs. 7 to 12. The final form of the bar is different, however, in that bolts 30 100 are employed for securing the cross bars to the ridge pole construction in lieu of the arrangement as shown in Figs. 8 and 9 comprising the notches 74 and 76. The arrangement shown in Fig. 14 also differs from that formerly described in that two bolts 79a are employed in lieu of the single bolt 79. In Fig. 14 the two pieces of glass shown mounted upon the cross bars are indicated by numerals 101.

In both constructions shown, the several top 40 and bottom rails, and the cross bars, as well as certain of the other parts are in the form of extruded structural shapes of aluminum alloy, made ready for use with a minimum of hand work thereon. Each of these forms is more or less 45 complicated, but by reason of my improved arrangement I am able to produce such parts in extruded metal which is adapted to withstand successfully all ordinary weather and climate conditions without any noticeable deterioration from 50 year to year, and to withstand severe acid atmospheric conditions such as would in a very short time destroy unprotected iron or steel structures. I have found that these forms can be produced successfully upon a commercial basis in an aluminum alloy of such characteristics as to enable 55 the metal to resist successfully seashore atmospheric conditions without any appreciable oxidation. By the use of my construction by which the cross bars 42 can readily be secured in any 60 desired adjusted position along the top and bottom rails, my construction is capable of very quick and easy installation. The required length of top and bottom rails can be sent to a job, together with the required number of cross bars, and such 65 frame structure parts can be readily applied to their final operative form regardless of the width of the pieces of glass which may be available for the job. If desired, different widths of glass can be used to advantage upon a single job, it being only necessary to provide openings for the screws 70 53 at the desired points for holding the cross bars in position. As a matter of fact, it would not even be necessary to employ screws 53 in connection with intermediate cross bars, it being sufficient if desired that merely the cross bars 75

at the ends of a section be secured to the top and bottom rails, although I prefer to secure each of the cross bars in rigid position by the use of such bolts 53.

While I prefer to employ the construction as shown in my drawings, it will be understood that my invention is not limited thereto except so far as the claims may be so limited by the prior art, it being understood that changes might well be made in the form of the construction without departing from the spirit of my invention. 80 85

I claim:—

1. A skylight comprising in combination a longitudinally extending bottom rail, a longitudinally extending top rail in spaced relation to said bottom rail, crossbars connected for sliding adjustment with said top and bottom rails, and pieces of glass supported by said rails and bars and serving to space said crossbars in operative position with respect to each other. 90 95

2. A skylight comprising in combination a longitudinally extending bottom rail, a longitudinally extending top rail in spaced relation to said bottom rail, crossbars having dovetailed head and groove connections with said top and bottom rails 100 and adjustably movable to any desired positions along said rails, and pieces of glass supported by said bars and serving to space said crossbars at the desired distance apart. 100

3. A skylight comprising in combination a longitudinally extending bottom rail, a longitudinally extending top rail in spaced relation to said bottom rail, said top rail having a longitudinal dovetail groove along its inner face opening towards said bottom rail, crossbars, means connecting said crossbars with said top and bottom rails and comprising heads in said groove, and means comprising pieces of glass filling the spaces between said crossbars from said top rail to the bottom rail. 105 110

4. A skylight comprising in combination a longitudinally extending bottom rail, a longitudinally extending top rail in spaced relation to said bottom rail, said bottom rail having a dovetail groove therealong on its inner face opening towards said top rail, a plurality of crossbars in 115 inclined position between said top and bottom rails secured in position on said bottom rail in any desired adjusted position therealong by heads having dovetailed connection with said groove, and pieces of glass interposed between 120 said crossbars serving to space said crossbars from each other. 125

5. A skylight comprising in combination a longitudinally extending bottom rail, a longitudinally extending top rail in spaced relation to 130 said bottom rail, said top and bottom rails having longitudinal dovetail grooves in their inside faces, crossbars, connecting plates extending from the ends of said crossbars with enlarged head portions engaging said dovetail 135 grooves for connecting said crossbars with the top and bottom rails, and pieces of glass supported by said rails and crossbars and controlling the spacing between said crossbars. 140

6. A skylight comprising in combination a longitudinally extending bottom rail, a longitudinally extending top rail in spaced relation to said bottom rail, said top and bottom rails having longitudinal dovetail grooves in their inside faces, cross bars, connecting plates extending from the ends of said cross bars with enlarged head portions engaging said dovetail grooves for connecting said cross bars with the top and bottom rails, said cross bars having flanges extending laterally therefrom at points below the upper edges of the 145 150

- bars and one of said rails having a groove on the inner face opening toward the other rail, and pieces of glass extending into said groove between said cross bars and resting on said flanges. 5
7. A skylight comprising in combination top and bottom rails in the form of extruded structural shapes of aluminum alloy and each having oppositely disposed web portions directed toward each other forming a dovetail groove therealong, cross bars having head portions at opposite ends adapted to be slid longitudinally of the rails into position to be held by said groove-forming web portions, and pieces of glass filling the spaces between the several bars and supported by said bars. 10
8. A skylight comprising in combination a top rail in the form of an extruded structural shape of aluminum alloy having oppositely disposed web portions directed toward each other forming a dovetail groove therealong, a bottom rail, cross bars having head portions adapted to be slid longitudinally of the top rail into position to be held by said groove-forming web portions, said top rail being provided with a flange portion in spaced relation above the upper one of said groove-forming web portions serving to provide a second groove in said rail open toward the bottom rail, and pieces of glass extending into said second groove in said top rail and filling the spaces between the several cross bars. 15
9. In a skylight, the combination of top and bottom rails in the form of extruded structural shapes of aluminum alloy comprising web portions forming the bodies of the rails, and each having bearing portions at opposite edges thereof located opposite the body portion in spaced relation to the body and in spaced relation to each other, cross bars having at opposite ends head portions of greater span than the distance between said bearing portions and adapted to be slid longitudinally of the rails into position to be held by said spaced parts, and pieces of glass filling the spaces between the several cross bars. 20
10. In a skylight, the combination of a bottom rail in the form of an extruded structural shape of aluminum alloy comprising a web portion forming the body of the rail, having a flange at its upper edge located opposite the body portion in spaced relation thereto and having a return bend portion at its lower edge in spaced relation to the body portion, cross bars having head portions of greater span than the distance between said flange and said return bend portion adapted to be slid longitudinally of the bottom rail into position to be held by said flange and return bend portion in snug engagement with the body portion, and pieces of glass filling the spaces between the several cross bars, said return bend portion serving with the body of the rail to form a trough for gathering and carrying away the water of condensation from the structure through openings at the lower edge of the rail. 25
11. In a skylight, the combination of a bottom rail in the form of an extruded structural shape of aluminum alloy comprising a web portion forming the body of the rail, having a flange at its upper edge located opposite the body portion in spaced relation thereto and having a return bend portion at its lower edge in spaced relation to the body portion, cross bars having head portions of greater span than the distance between the several cross bars, said flange and return bend portion in snug engagement with the body portion, pieces of glass filling the spaces between the several cross bars, said return bend portion adapted to be slid longitudinally of the bottom rail into position to be held by said flange and return bend portion in snug engagement with the body portion, pieces of glass filling the spaces between the several cross bars, said return bend portion serving with the body of the rail to form a trough for gathering and carrying away the water of condensation from the structure through openings at the lower edge of the rail. 30
12. In a skylight, the combination of a longitudinally extending bottom rail, a plurality of cross bars extending obliquely upwardly and inwardly from said bottom rail and connected thereto and each in the form of an extruded structural shape of aluminum alloy comprising a vertically disposed web portion forming the body of the cross bar, flanges extending in both directions from said web portion near its upper edge providing supporting bearings, other flanges providing condensation gutters at opposite sides of the bar below said first named flanges, said last named flanges being provided with longitudinally extending grooves on their bottom faces, pieces of glass supported by said bearings and serving to close the spaces between said cross bars, and trough means below the lower ends of said cross bars in position to receive the water of condensation from said grooves at the lower ends of the cross bars. 35
13. In a skylight, the combination of a longitudinally extending bottom rail comprising a turned back flange portion providing a trough along its bottom edge, a gutter supported inside and below said bottom rail, a flange extending inwardly and downwardly from the lowermost return bend portion of said trough arrangement and overhanging said gutter, cross bars connected at their lower ends with said bottom rail, and pieces of glass filling the spaces between said cross bars. 40
14. In a skylight, the combination of two longitudinally extending bottom rails at opposite sides of the skylight opening, a ridge pole structure in elevated position between said bottom rails, cross bars comprising vertical disposed webs, means for directly connecting the upper ends of the webs of said cross bars together, means for connecting the lower ends of the said cross bars to the bottom rails, said webs being provided with transversely disposed flanges at their upper edges and being attached at such flanges to the ridge pole structure. 45
15. In a skylight, the combination of two longitudinally extending bottom rails at opposite sides of the skylight opening, a ridge pole structure comprising two vertically spaced flanges on either side of a central web, cross bars comprising vertically disposed webs, means for directly connecting the upper ends of the webs of said cross bars together and for connecting the lower ends of the cross bars to the bottom rails, the vertically disposed web of each cross bar being provided with laterally extending flanges near the upper edge thereof, the web of each cross bar and one of the flanges of said ridge pole structure having notched engagement with each other. 50
16. In a skylight, the combination of a gable supporting structure, a plate extending along the peak thereof with a marginal portion sloping 55

downwardly at either side of said peak, and provided with an upwardly extending flange at each longitudinal edge forming a condensation gutter, and movable window frames, each including an upper rail extending into said gutter at the base of the respective flanges to form a hinged connection for the respective frames.

17. In a skylight, the combination of a longitudinal plate supported in elevated position and provided with a sloping marginal portion flanged at its lower edge to form a gutter, and a movable window frame including an upper rail extending into said gutter at the base of said flange to form a hinged connection for the frame.

18. In a skylight, the combination of a longitudinal plate supported in elevated position and provided with a sloping marginal portion flanged at its lower edge to form a gutter, and a movable window frame including an upper rail extending into said gutter at the base of said flange to form a hinged connection for the frame, said frame including a plurality of rafters with the upper rail provided with a groove on its lower face for connection with said rafters.

19. In a skylight, the combination of a plate supported in elevated position with a sloping marginal portion, and a flange at the lower edge of said portion, a ridge member supported above said plate and provided with an inwardly bent

flange on its under side and a movable window frame including an upper rail extending at its lower edge into the juncture of said plate and flange thereof to form a hinged connection, said upper rail being provided also with a pair of spaced flanges at its upper edge adapted to receive there between the flange on the ridge member when the frame is in closed position to form a seal between the frame and the ridge member.

20. In a skylight, the combination of a longitudinally extending bottom rail, a plurality of cross bars extending obliquely upwardly and inwardly from said bottom rail and connected thereto and each in the form of a vertically disposed web portion forming the body of the cross bar, flanges extending in both directions from said web portion near its upper edge providing supporting bearings, other flanges at opposite sides of the bar below said first named flanges, said last named flanges being provided with longitudinally extending grooves on their bottom faces, pieces of glass supported by said bearings and serving to close the spaces between said cross bars, and trough means below the lower ends of said cross bars in position to receive the water of condensation from said grooves at the lower ends of the cross bars.
